(57) **CLAIM**

The ornamental design for a container for denture base creation, as shown and described.

DESCRIPTION

FIG. 1 is a front view of a container for denture base creation showing our new design; FIG. 2 is a rear view thereof; FIG. 3 is a left side view thereof; FIG. 4 is a right side view thereof; FIG. 5 is a top plan view thereof; FIG. 6 is a bottom plan view thereof; FIG. 7 is a cross-sectional view thereof, taken along line 7-7 in FIG. 5; FIG. 8 is a cross-sectional view thereof, taken along line 8-8 in FIG. 5; FIG. 9 is a top perspective view thereof; FIG. 10 is another top perspective view thereof; FIG. 11 is a bottom perspective view thereof; and, FIG. 12 is another bottom perspective view thereof. The container for denture base creation shown in FIGS. 1-12 is entirely transparent. The dot-dash broken lines shown in FIG. 5 are included to represent the indication of the cross-sectional view and form no part of the claimed design.
